UNITED STATES PATENT OFFICE.

JOSHUA POOL AND JOSEPH POOL, OF GREENSBURG, INDIANA.

DESIGN FOR MONUMENTS.

Specification forming part of Design No. **11,467**, dated October 21, 1879; application filed September 27, 1879.
[Term of patent 7 years.]

To all whom it may concern:

Be it known that we, JOSHUA POOL and JOSEPH POOL, of Greensburg, in the county of Decatur and State of Indiana, have originated and designed a new Monument, of which the following is a full, clear, and exact description, reference being had to the accompanying drawing, making part of this specification.

The nature of our design is fully represented in the accompanying drawing; and it consists of a monument of four sections, which are to be mounted on a square base, A, made in one or more pieces. The first section, B, of our monument or design is a base, which is square, finished at the top with projecting moldings at each of the four corners to receive the bases of the four pillars, which are formed in each of the four corners of the die or section D. Part of the space between the projections at the corners of the base B is flush with the surface, being relieved by a bevel angling from the surface of the base to the lower line of the die D, which rests on the base B.

On the base B is mounted the square die D, the surface in each of the four corners being cut away, forming in each a pillar or projection, D', each pillar having a base at each lower corner of the die to fit the projection at each corner of the base B. On each side of the die D is a raised panel.

The cap or section E is square, and finished at its bottom side to correspond with the die D and pillars D', and is finished at its upper part with the roof-shaped gables E' on its four sides, with a square tapering center, E², finished at its top to fit the square shaft F.

The shaft or section F is chamfered in each of the four corners, and is finished near its top with a gable, H, on each of its four sides, in or between which, and projecting above the gables, is a square tapering center, G, with a diamond-shaped apex, I, forming the top of the shaft.

It is obvious that the moldings on each piece or section may be modified, and other moldings, formed of straight or curved lines, substituted, without departing from the essential features of our design.

What we claim as new, and desire to secure by Letters Patent, is—

1. The design of a sectional monument, as shown, consisting of the square base B, fitted to the die D above, which, in its turn, is fitted to the cap E, surmounted by the shaft F, with its gables H, tapering center G, and diamond apex I, all to be mounted on the square base A, as shown and described.

2. The design of a monument as a whole, with its various sections fitted together, having angles and faces, and each section of the design separately, and each part of each section of the design, substantially as shown and described.

In testimony whereof we have signed our names to this specification in the presence of two subscribing witnesses.

JOSHUA POOL.
JOSEPH POOL.
